RAIL JOINT CHAIR

Filed Dec. 10, 1930

FIG. 1

FIG. 2

INVENTOR

Charles Wesley Burt

John Warkett
His Attorney

UNITED STATES PATENT OFFICE

CHARLES WESLEY BURT, OF SYDNEY, NOVA SCOTIA, CANADA

RAIL JOINT CHAIR

Application filed December 10, 1930, Serial No. 501,351, and in Canada December 5, 1929.

This present invention relates to certain new and useful improvements in a rail joint chair.

The primary object of the invention resides in the provision of a rail joint chair which supports the rail on the bottom of the flange as well as under the ball of the rail.

The invention has for another object the provision of a rail joint chair of the character stated which provides ample bearing on the ties, thus eliminating the use of tie plates under the rail joint chair.

The invention has for a further object the provision of a rail joint chair of the character stated which makes the joint as strong as the rail, thus reducing the deflection when the wheels of the rolling stock pass over the joint.

The invention has for a still further object the provision of a rail joint chair of the character stated which provides a most substantial and smooth joint, eliminating the noise, and preventing the wear on the end of the rails.

The invention has for a still further object the provision of a rail joint chair of the character stated which can be readily rolled in a standard rolling mill in long bars, sheared and punched in the flange thereof for spikes to provide a substantial fastening to the ties without requiring any expensive machine work.

The invention has for a still further object the provision of a rail joint chair of the character stated which may be produced at small cost, and sold at a popular price with good profit, thus providing a commercially attractive proposition.

To the accomplishment of these and related objects as shall become apparent as the description proceeds, my invention resides in the construction, combination and arrangement of parts as shall be hereinafter more fully described, illustrated in the accompanying drawings and pointed out in the claim hereunto appended.

The invention will be best understood and can be more clearly described when reference is had to the drawings forming a part of this disclosure, wherein like characters indicate like parts throughout the several views.

In the drawings:—

Figure 1 is a side elevation of the improved rail joint chair, showing the same in use; and

Figure 2 is a transverse vertical section therethrough, taken substantially on the plane of line 2—2 of Figure 1, looking in the direction indicated by the arrows. 55

Referring more in detail to the drawings, it is to be noted that the rail joint chair includes complementary members, each of 60 which has a base portion 6 adapted to fit under the rail base 7 and extend longitudinally thereof. Each base portion 6 has an outwardly directed longitudinal flange 8 through which spike openings 9 may be 65 punched or otherwise provided for the spikes 10 to be extended through and driven into the ties 11 across which the complementary members are mounted. These complementary members are provided with grooves or corrugations 6a on their under faces and are also adapted to rest in depressions or pockets 12 provided therefor in the upper face of the ties 11 so as to prevent spreading of the rail. 70 To compensate for this inclining of the complementary members, they have their base portions 6 bevelled on their upper faces so as to support the rail base 7 in proper horizontal plane thereon. If desired, the grooves or corrugations 6a or the depressions 75 80 or pockets 12, or both, may be dispensed with and the complementary members 6 mounted in upright position on the ties 11. The complementary members are employed at a rail joint and the body portions 13 of said members rising from the flanges 8 thereof and extending upwardly toward one another in slightly inclined planes are adapted to extend over the upper face of the rail base 7 of the opposed rail ends forming the rail 90 joint and said body portions 13 of the complementary members normally rest upon and bind on the upper face of the rail base 7, at the inner longitudinal edges 14 of said body portions 13 of the complementary members 95 and near the connection of the longitudinal inner edges of the rail base 7 with the upstanding rail web 15. The upstanding or fish plate portions 16 of the complementary members rise from the body portions 13 100

thereof so as to have their inner faces normally spaced from the opposite faces of the rail web 15. The upper edges 17 of the complementary members are bevelled or inclined outwardly so as to firmly engage the bevelled under faces 18 of the rail head or tread 19. The upper edges 17 of the upstanding portions 16 of the complementary members bind against and at all times firmly contact with the under faces 18 of the rail head or tread 19. It is also to be noted that bolt openings 20 are provided in the upstanding portions 16 of the complementary members registering with corresponding bolt openings 21 in the rail web 15 to receive the bolts 22 extended through said web 15 of the rail and through the upstanding portions 16 of the complementary members, with lock nuts 23 or the like carried on the threaded ends of the bolts 22. Attention may be also directed at this time to the main part of the base portions 6 of the complementary members binding against the under face of the rail base 7, at all times. Likewise, it is to be noted that the opposed edges of the base portions 16 of the complementary members are normally spaced apart beneath the centre of the rail base 7 and spaces are also provided between the outer longitudinal edges of the rail base 7 and the upstanding inner walls between the base portions 6 and the body portions 13 of said complementary members, thus permitting inward movement of said complementary members on the opposite sides of the rail sections, if required, for an adjustment of said complementary members and said rail sections.

As the construction of the device has thus been described in detail, brief reference is now had to its use and modus operandi: The rail ends are effectively and firmly held in the proper horizontal plane and outward spreading of the rail sections is prevented. Furthermore, the rail end sections are firmly held between and clamped by the complementary members constituting the rail joint chair, with a binding action beneath the rail base 7, on either side and again on the upper face of the rail base 7, near the connection thereof with the rail web. Further binding is assured, at all times between the outwardly inclined faces 17 of the upper edges of the upstanding or fishplate portions 16 of the complementary members and the inclined under faces of the rail head or tread 19. Thus, the binding action is assured as the chair is subjected to exceptional strain and at the other points the parts are normally separated, thus permitting sufficient expansion and contraction of the parts, to assure the highest efficiency of results and automatic adjustment or regulation of the various parts, with respect to one another. When required, the lock nuts 23 may be readjusted on the bolts 22, to bring the complementary

members into firm and proper engagement with the rail section ends. Firm holding of the rail section ends in proper relation, at all times, is assured and side spreading of the rails, at the joints thereof is prevented by this improved rail joint chair. 70

From the foregoing description taken in connection with the accompanying drawings, it will be manifest that a rail joint chair is provided that will fulfill all the necessary requirements of such a device but as many changes could be made in the above description and many apparently widely different embodiments of my invention may be constructed within the scope of the appended 80 claim without departing from the spirit or scope thereof, it is intended that all matters contained in the said accompanying specification and drawings, shall be interpreted as illustrative and not in a limited sense. 85

Having thus described my invention, what I claim as new and desire to secure by Letters Patent is:—

A rail joint chair including the combination with the opposed ends of rail sections and cross ties beneath the same provided adjacent their ends with inclined pockets in their upper faces having upstanding outer end walls; of a pair of complementary rail joint chair members having base portions with their under faces beveled transversely and serrated for engagement with the bottom wall of said pockets in said cross ties; the outer chair member engaging against the upstanding outer end wall of said pocket to prevent outward movement of said complementary rail joint chair members on said ties; said complementary rail joint chair members having recesses in their base portions to receive the base portions of said rail section ends with the base portions of said complementary rail joint chair members binding on the underface and the upper face of said base portions of the rail section ends; said complementary rail joint chair sections having upstanding portions opposite the web portions of said rail section ends with the upper edges of said upstanding portions of the complementary rail joint chair members bearing against the underface of the tread portions of said rail section ends; means for firmly retaining the upstanding portions of said complementary rail joint chair members in position on opposite sides of said rail section ends; and means for firmly retaining said base portions of the complementary rail joint chair member on said ties. 100 110 115 120 125

In testimony whereof I hereunto affix my signature.

CHARLES WESLEY BURT. [L.S.] 125
